Des. 240,085
Patented May 25, 1976

240,085

BIOLOGICAL STORAGE CONTAINER

Dennis J. Reisdorf, Santa Ana, Calif., assignor to Baxter
Laboratories, Inc., Deerfield, Ill.

Filed Aug. 14, 1974, Ser. No. 497,430

Term of patent 14 years

Int. Cl. D9—03; D24—99
U.S. Cl. D83—1 U

FIG. 1.

FIG. 2.

FIG. 3.

FIG. 4.

FIG. 5.

FIG. 1 is a top perspective view of a biological storage container with the cover closed, showing my new design;

FIG. 2 is a top perspective view of the container with the cover open and showing removable contents for clarity of illustration;

FIG. 3 is a top perspective view of the container with the cover open and with the contents removed;

FIG. 4 is a top plan view of the container with the cover open and with the contents removed; and

FIG. 5 is a sectional view taken on the line 5-5 of FIG. 1.

I claim:

The ornamental design for a biological storage container, as shown and described.
